US00D597572S

(12) **United States Design Patent**
Tsai

(10) **Patent No.:** **US D597,572 S**
(45) **Date of Patent:** **** Aug. 4, 2009**

(54) **PORTABLE HEAT SEALING MACHINE**

(76) Inventor: **Mao Bang Tsai**, Jidali Industrial Zone, Gonghe Village, Shajing Town, Baoan, Shenzhen City, Guangdong (CN)

(**) Term: **14 Years**

(21) Appl. No.: **29/327,735**

(22) Filed: **Nov. 12, 2008**

(51) **LOC (9) Cl.** 15-99

(52) **U.S. Cl.** D15/146

(58) **Field of Classification Search** D8/49, D8/50, 105; D15/144, 145, 146; 53/373, 53/374.8, 374.9, 390, 405, 432-434, 510-512, 53/DIG. 2; 156/497, 515, 583.1-583.91; 219/227, 229, 230, 233, 240, 243

See application file for complete search history.

(57) **CLAIM**

The ornamental design for a portable heat sealing machine, as shown as described.

DESCRIPTION

FIG. 1 is a perspective view of a portable heat sealing machine, showing my new design;

FIG. 2 is a front view thereof;

FIG. 3 is a rear view thereof;

FIG. 4 is a left side view thereof;

FIG. 5 is a right side view thereof;

FIG. 6 is top view thereof;

FIG. 7 is a bottom view thereof;

FIG. 8 is a referential perspective view thereof with a suction pads attached to the bottom of the portable heat sealing machine; and,

FIG. 9 is a referential perspective view thereof with a detachable holder with an adhesive tape attached to the bottom of the portable heat sealing machine.

The broken line showing of environmental structures is for illustrative purposes only and forms no part of the claimed design.
